UNITED STATES PATENT OFFICE.

JAMES C. DAVIS, OF HINSDALE, ILLINOIS, ASSIGNOR TO AMERICAN STEEL FOUNDRIES, OF CHICAGO, ILLINOIS, A CORPORATION OF NEW JERSEY.

METHOD OF AND MEANS FOR RECLAIMING MOLDING-SAND.

1,393,092.

Specification of Letters Patent.

Patented Oct. 11, 1921.

Application filed May 2, 1918. Serial No. 232,114.

To all whom it may concern:

Be it known that I, JAMES C. DAVIS, a citizen of the United States, residing at Hinsdale, in the county of Cook and State 5 of Illinois, have invented certain new and useful Improvements in Methods of and Means for Reclaiming Molding-Sand, of which the following is a specification.

This invention relates to a method of and 10 means for reclaiming molding sand.

One of the objects of this invention is to reclaim used molding sand in a novel and efficient manner.

Another object is to provide a simple, 15 compact and durable device by means of which molding sand may be thoroughly cleaned for permitting its further use.

These and other objects are accomplished by means of the mechanism disclosed by 20 the accompanying sheets of drawings, in which—

Figure 1 is a front elevation, parts being in section, of my sand reclaimer;

Fig. 2 is a fragmentary detail sectional view of the sand reclaimer, showing the fan or beater for violently treating the sand and also showing the sand and dust exits;

Fig. 3 is a front elevation of a sand separator attachment; and,

Fig. 4 is a detail sectional view, taken in the planes of irregular line of 4—4 of Fig. 1.

Molding sand and bonding material are relatively expensive and where molding is done on a large scale the handling of such material is one which must be seriously considered, even though the sand is disposed of after once being used. Merely using sand a single time is extremely uneconomical. Therefore, the question of reclaiming sand 40 after it has been used is one which has been considered seriously, especially by companies doing foundry work on a large scale.

It is a well appreciated fact in the molding art that the voids of sand, or, in other 45 words, the spaces between the grains of sand serve an important function of permitting the escape of gases during the pouring of a mold. Accordingly, the greater amount of voids, the more readily will the 50 gases escape. However, it is necessary that the grains of sand be bound together to a certain degree by some medium, such as ground clay, and the like.

Care must be taken to avoid the use of an 55 excess amount of bond material, not only

from the standpoint of expense, but also when the percentage of the bond is raised beyond a certain limit it causes a reduction in the average fusing point and it further reduces the volume of the voids in the sand, 60 the former being an instrument in causing roughness, and the latter might develop a number of defective causes in the foundry product. All bonding materials have a relatively low fusing point, and, as stated above, 65 also to more effectively serve their purpose, the bonding materials are ground and pulverized to a very fine consistency and these qualities constitute their inherent weakness and distract from their permanency by reducing their ability to withstand the high 70 temperatures which are developed in the casting period and to which the sand in immediate contact and adjacent the casting is subjected. Molding sand is a poor conductor of heat, due primarily to the voids and the presence of air therein, and as a consequence the high temperature resulting from the molten metal does not extend beyond a 75 point relatively close to the mold cavity. 80 The bonding material beyond this zone of high temperature does not become heated to a point which has a very material effect on its condition, and for that reason the simple process of cutting up or mixing or tempering is sufficient renovation to again place it 85 in condition for further use. On the other hand, the bonding material which is contained in the high temperature area suffers a decided change and by total disintegration 90 or surface fusion, loses permanently its bonding or adhesive properties. The grains of sand composing the layer of sand which comes in contact with the molten metal are fused immediately into a thin scale and 95 rendered useless for any further purpose. The remaining sand grains within the high temperature zone, and which do not come in contact with the metal, are heated to a point of iridescence and perhaps to surface fusion. The bonding material with 100 which it is surrounded and which is less susceptible to high temperature, is totally reduced and in this condition combines with the fused or partially fused surface of the 105 sand grains. Owing to the plastic condition of these sand grains, the decomposed bonding material is embedded or attached firmly to the surface of the sand. This transformation is an important one from a 110

standpoint of reclaiming, and it is admittedly the one problem which is difficult to overcome. The tenacity with which this decomposed bond is attached or fused to the 5 surface of the sand is remarkable. To prepare grains of sand in this condition for reuse is the result of continued experiment for a long period of time. I find that to prepare grains of sand in this condition for 10 reuse requires a process of some mechanical violence and the severity of the action must be sufficient to break down and remove from a large portion of the sand grains the attached particles of decomposed bonding 15 material.

By means of my method and the mechanism shown, the used sand is fed to a rapidly revolving bladed member, which strikes the 20 grains of sand with tremendous force, driving the grains against the walls of a receptacle for breaking away the decomposed bonding material and the fused surface formed on the grains of sand, the sand being cleaned by abrasion and attrition, both 25 by the sand grains being violently treated and agitated one against the other and by driving the individual sand grains against the cleaning surface of the receptacle in which the action is taking place. 30 My device treats sand in a manner such that all objectional matter is removed. This method is positively effective and economical so that when the reclaimed sand is discharged from the machine it is ready to be 35 utilized again for molding purposes without further delay or treatment. The theory upon which my centrifically operated sand cleaner is based is that the reclamation of molding sand is primarily a process of 40 cleansing the grains of sand by removing from their surface all adherent particles of foreign material.

By referring to the figures of the drawings it will be noted that I have shown a 45 scrubbing chamber 10, with a tangential outlet 11 for the exit of the sand after it has been cleaned. Fitting within this chamber 10 at the bottom, where the greatest abrasion is localized is a wearing ring 12. This 50 ring is so arranged that it can be withdrawn and replaced when it becomes worn, thus protecting the remainder of the apparatus from excessive wear. Rotatively mounted in the scrubbing chamber 10 is a disk 13, preferably of steel, provided with a relatively large number of radially and vertically extending blades or wings 14. This 55 fan structure is mounted upon a vertically arranged shaft 15, which is driven by a motor 16 directly connected to the shaft. 60 Directly above the main scrubbing chamber 10 is an annular drum 17, which serves as a dust separating device. This drum also is provided with a tangential opening or exit 65 18 for carrying off dust laden air to a proper machine through the medium of its own

disposal. In practice dust collectors are connected directly to the outlet of the drum. This drum 17 has a bottom circular flange 19, which extends radially toward the center thereof and serves as a partition or baffle 70 to prevent the sand grains from entering the drum or dust chamber 17, thereby serving the purpose of a separator. The top of the drum 17 is closed, with the exception of an opening 20 in the center from which conduit 21 extends down into close proximity to the fan 13. Air passes down through the pipe or conduit 21, said conduit preventing this clean air which passes therethrough from interfering with the upward flow of 80 dust-laden air passing from chamber 10 into the chamber or drum 17. This conduit 21 also serves the function of guiding the air currents in the proper direction, which is facilitated by means of the circular flange 85 22, formed at the bottom of the conduit 20. In order to facilitate the supply of air to the conduit 21, the motor 16 is elevated and supported by a spider 23.

Extending down through the conduit 21 is 90 a suitable feed pipe 24, which directs the flow of sand from a source of supply 25 to the revolving fan 13 near the center thereof. Directly below the fan 13 is a bowl shaped bottom plate 26, which provides clearance 95 below the fan for taking care of any surplus sand in the event that the machine is fed too heavily. It will be noted that this plate 26 is provided with holes 27 for the automatic discharge of any surplus sand and 100 also for any scale or foreign matter which may be accidentally fed into the machine.

In the operation of this machine, the motor 16 is set in motion thereby causing the fan to be rotated at a relatively high rate 105 of speed. The blades or wings 14 act as a horizontal fan, creating a circular movement of the air within the chamber 10. Centrifugal force causes this air to crowd away from the center of the chamber thereby forming 110 a vacuum, which creates a suction of clean air down through the conduit 21. The air which enters through the conduit 21 is circulated through the chambers 10 and 17 and is discharged through the dust outlet 18. 115

Sand is fed into the supply pipe 24 in a continuous stream equal to the capacity of the machine and is directed onto the central portion of the rapidly revolving fan 13. Through centrifugal force and aided by the 120 blades 14, the used sand is swept with terrific velocity out against the wearing ring 12 in the scrubbing zone. Due to its tangential trajectory imparted by the movement of the rotating fan and consequently aided by the 125 circular movement of the air blast created also by the fan blades, the sand travels in a helical direction upward until it strikes the 130

momentum. The flange 19, at the bottom of chamber 17 prevents any of the sand from entering the auxiliary chamber 17 and compels its continued circular travel until it 5 takes the natural outlet 11 in the regular manner hereinabove described.

Owing to the air pressure created within the device and also the pressure of the air entering through the conduit 21, the dust 10 laden air passing from chamber 10 to chamber 17 is forced out of the scrubber and through the opening 18 toward a dust collector.

If it is desired to separate the large grains 15 of sand from the smaller grains, the same may be accomplished by means of a separating device 28, which may be connected to the exit conduit 29 of the scrubber. This separating device may be of any suitable type. 20 The one herein disclosed includes a chute 30, through which the sand passes and is directed down over plates 31 which are pivotally mounted at a central point 32 by means of which their inclination may be

25 varied. Air may be drawn through the spaces 33 between the plates 31 and exhausted through the rear of the plates and out through the upper exit 34 of the separator. In this way the lighter or smaller grains of

30 sand will be drawn into the passageways 33, by the suction of the air and will fall upon the plates. Thus grains which are drawn over the plates 31 will fall into the rear chamber 35 and may be removed therefrom

35 by opening a door 36. Some of the heavier grains of sand which fall directly past the front edges of the plates 31 are drawn into the passageways 33 and slide downwardly thereon, passing from the separator through

40 a chute 37. In this manner reclaimed sand may be separated into different grades. This separator also acts as an additional means for freeing the sand of any dust which may have passed through the discharge opening

45 11 of the scrubber.

It will be appreciated, of course, that various types of separators and auxiliary cleaners may be used in connection with my scrubber, also my sand reclaiming device 50 may take various forms and it is my intention to cover all such modifications of forms, falling within the spirit and scope of the following claims.

I claim:

55 1. An apparatus for reclaiming used molding sand, including in combination, a casing, a horizontally rotatable fan therein, means for delivering the used sand to said fan near the center thereof, a horizontally disposed flange extending inwardly of said casing above said fan, said flange defining an opening of less size than the casing, the

casing having an exit opening immediately beneath said flange and also an exit opening above said flange, means for driving said 65 fan, the latter driving the sand against the walls of the casing, and giving the sand an upward helical motion whereby the sand is driven against said flange and outwardly over said lower exit. 70

2. An apparatus for reclaiming used molding sand, including in combination, a casing, a horizontally rotatable fan therein, means for delivering the used sand to said fan near the center thereof, a horizontally disposed flange extending inwardly of said casing above said fan, said flange defining an opening of less size than the casing, the casing having an exit opening immediately beneath said flange and also an exit opening 80 above said ring, means for driving said fan, the latter driving the sand against the walls of the casing, and giving the sand an upward motion whereby the sand is driven against said flange and outwardly over said 85 lower exit.

3. In a device for reclaiming used molding sand, including in combination, a plurality of communicating chambers, each chamber having an outlet, a fan in one of said chambers, a partition between said chambers to restrict the passage-way therebetween, means for supplying used sand to said fan, means for rotating said fan whereby said fan causes said sand to be driven against the walls of 90 said chamber adjacent said fan for cleaning it and be passed out through the outlet in said chamber and causing dust removed from said sand to pass into the other chamber and outwardly through its opening, said 95 partition serving to prevent the sand from passing from one chamber to the other. 100

4. The method of reclaiming used molding sand, consisting in imparting a velocity to the sand, and delivering said moving 105 stream of sand against a relatively fixed surface for cleaning said sand and then removing by a stream of air the refuse broken from the sand by the impact with the fixed surface and with adjacent sand grains. 110

5. The method of reclaiming used molding sand, consisting first in subjecting said sand to a violent centrifugal motion and then selectively discharging the cleaned sand and the refuse material removed therefrom, said 115 discharging being effected by reason of air currents set up by said centrifugal motion.

Signed at Chicago, Illinois, this 16th day of April, 1918.

JAMES C. DAVIS.
